UNITED STATES PATENT OFFICE.

ALBERT P. KNAUBER, OF MILWAUKEE, WISCONSIN.

ROWBOAT MOTOR.

Application filed January 11, 1926. Serial No. 80,539.

This invention relates to improvements in row boat motors.

It is one of the objects of the present invention to provide a two cylinder row boat motor having opposed, air cooled cylinders.

A further object of the invention is to provide an air cooled motor having novel means for forcefully directing air onto and around the cylinders.

10 A further object of the invention is to provide a row boat motor which is pivotal with respect to the rear of the boat to permit a movement of the motor in shallow water so that the propeller will not be injured, there being means however for quickly manually locking the motor in normal unpivotal position.

20 A further object of the invention is to provide an air cooled motor of the class described in which the cylinders are encased by a housing to protect the same from rain and water.

25 A further object of the invention is to provide an air cooled row boat motor which is of very simple construction, is strong and durable, is efficient in operation, and is well adapted for the purposes set forth.

30 With the above and other objects in view the invention consists of the improved boat motor and its parts and combinations as set forth in the claims, and all equivalents thereof.

35 In the accompanying drawings in which the same reference characters indicate the same parts in all of the views:

Fig. 1 is a front view of the improved row boat motor, part being broken away to show details of construction;

40 Fig. 2 is an end view of the motor shown attached to the rear portion of a boat;

Fig. 3 is an enlarged detail view of one of the cam locking members for holding the motor in unpivotal position;

Fig. 4 is a sectional view taken on line 4-4 of Fig. 5;

Fig. 5 is an enlarged plan view of the fly wheel, the crank handle being omitted; and

50 Fig. 6 is a fragmentary view of the end portion of a boat showing how the motor is attached thereto and the locking means.

Referring now more particularly to the drawing it will appear that the improved motor employs a pair of oppositely disposed cylinders 8 secured to opposite sides of the crank case 9, the cylinders being of the air

cooled type with cooling fins 10. Extending vertically through the crank case is a propeller shaft 11 carrying a propeller (not shown) at its lower end.

60 The upper end portion of the shaft has keyed thereto a fly wheel 12 having a handle 13, by which means the motor is cranked when starting. As shown particularly in Figs. 4 and 5 the fly wheel is formed with a plurality of radial downwardly inclined blades 14. Thus, when the fly wheel is revolving said blades will draw in air and direct it onto the cylinders to cool the same.

65 To protect the cylinders from rain and other water, a housing 15 is provided. The arrangement of said housing is shown particularly in Figs. 1 and 2 and the same is flanged and open at its upper end to accommodate the fly wheel 12 but protectively encloses the cylinders and crank case.

70 Depending from the cylinders are a pair of arms 16 through the lower ends of which pivot bolts 17 extend, and pivotally mounted on each bolt is a bracket member 18, formed particularly as shown in Fig. 6, with turn bolts 19 for clamping the members to the stern of a boat 20. This arrangement permits a rocking or pivotal movement of the motor with respect to the boat which is desirable in shallow water to prevent injury to the propeller. However, in deeper water

75 the motor should be rigidly locked in normal vertical position and to that end the upper portions of each of the bracket members are formed with integral discs 21 having cam faces 22 divided into quadrants, as shown.

80 Also pivotally mounted on the bolts 19 are locking members 23, the inner faces of which are cam-like to engage the cam faces 22.

85 The handle portions 24 of the members 23 are joined by a U-bar 25 whereby the locking members may be operated simultaneously. In the position shown in Fig. 1

90 with the shoulders of the cam faces abutting, pivotal movement between the brackets and motor is permitted. However, an upward lift on the bar 25 will move the members 23

95 to cause a wedging action whereby pivotal movement is prevented and the motor is reasonably locked in fixed position.

100 Due to the fact that many portions of the motor are of usual construction, only the novel features have here been described in detail.

110 From the foregoing description it will be seen that the improved row boat motor is

- of the air cooled type with a pair of opposed cylinders surrounded by a protective housing and fly wheel is utilized to force and circulate air about the cylinders. The 5
motor is pivotal with respect to the boat when desired, and may be locked in rigid position for normal use. Also the motor is simple in construction and effectively combines novel and advantageous features.
10. What I claim as my invention is:
1. In a motor propeller for boats, the combination of an engine, a pair of mounting brackets each pivotally connected with the engine and adapted for attachment to a boat, the pivotally mounted portions of said brackets having cam faces, and a manually operable locking member having complementary cam faces engaging said first-mentioned cam faces and movable to wedgingly engage the same to prevent movement between the engine and said brackets.
  2. In a motor propeller for boats, the combination of an engine having a pair of depending arms, a pivot bolt extending transversely through each of said arms, a mounting bracket carried by each bolt and adapted for attachment to a boat, the pivotally mounted portions of said brackets having cam faces, a lever pivotally mounted on each bolt adjacent said brackets, said levers having complementary cam faces and movable to wedgingly engage the first-mentioned cam faces to prevent movement between the engine and brackets, and a bar connecting said levers for manually, simultaneously operating the same.
  3. In a motor propeller for boats, the combination of a crank case, a pair of oppositely disposed air cooled cylinders extending laterally therefrom, a propeller shaft extending transversely through the crank case, and fly wheel means at the upper end of the shaft to circulate air about the cylinders.
  4. In a motor propeller for boats, the combination of a crank case, a pair of oppositely disposed air cooled cylinders extending laterally therefrom, a propeller shaft extending transversely through the crank case, a fly wheel at the upper end of the shaft, and a plurality of radial, downwardly inclined blades within said fly wheel to cause circulation of air about said cylinders.
  5. In a motor propeller for boats, the combination of a crank case, a pair of oppositely disposed air cooled cylinders extending laterally therefrom, a propeller shaft extending transversely through the crank case, a fly wheel at the upper end of the shaft, means within said fly wheel to cause circulation of air about the cylinders, and a protective housing enclosing the cylinders and crank case and open the top to accommodate the fly wheel.
  6. In a motor propeller for boats, the combination of a crank case, a pair of oppositely disposed air cooled cylinders extending laterally therefrom, a propeller shaft extending transversely through the crank case, a fly wheel at the upper end of the shaft and arranged to circulate air about the cylinders, said fly wheel having a plurality of radial, downwardly inclined blades, a protective housing enclosing the cylinders and crank case and open at the top to accommodate the fly wheel, a pair of arms depending from the cylinders, a pivot bolt extending transversely through each of said arms, a mounting bracket carried by each bolt and adapted for attachment to a boat, the pivotally mounted portions of said brackets having cam faces a lever pivotally mounted on each bolt adjacent said brackets, said levers having complementary cam faces and movable to wedgingly engage the first-mentioned cam faces to prevent angular movement between the motor and boat, and a bar connecting said levers for manually, simultaneously operating the same.

In testimony whereof, I affix my signature
ALBERT P. KNAUBER.
